FACE GUARD RESTRAINING DEVICE

Albert Mueller, Kiester, Minn.

Application November 19, 1947, Serial No. 786,897

3 Claims. (Cl. 119—142)

1

This invention relates to a boss cow tamer and particularly to a halter type tamer.

It has long been a problem for farmers to prevent one cow in the herd from running against and butting the other cows with her head and thus injuring many of the cows by bruising their side portions and udders and by pushing them against fences and the like and in general making the whole herd nervous and discontented. An uneasy herd will not produce the quantity of milk that a contented herd will produce.

It is an object of my invention to overcome the boss cow problem by providing a novel and improved halter adapted to be mounted on the boss cow's head and to hurt said cow when she butts her head against another cow or other object.

More specifically it is an object to provide a halter having at least one pointed prong adapted to be held in normally spaced relation from the cow's head and to be pressed against said head when pressure is applied against the outer side thereof.

These and other objects and advantages of my invention will more fully appear from the following description made in connection with the accompanying drawings wherein like reference characters refer to similar parts throughout the several views and in which;

Fig. 1 is a side perspective view of my cow halter as mounted on the head of a cow and showing one side of said halter;

Fig. 2 is a perspective view of the cow halter illustrated in Fig. 1 showing the other side thereof; and,

Fig. 3 is a transverse vertical sectional view taken substantially along the line 3—3 of Fig. 2 and showing the detail of the prongs and resilient spacing element of the bar member.

As illustrated in the accompanying drawings, I provide a halter having an upper head strap 5 adapted to fit behind a cow's ears and embrace the upper rear portion of the cow's head as best shown in Fig. 1. An upper nose strap 6 is adapted to fit over an intermediate portion of the cow's nose slightly below the cow's eyes as best shown in Fig. 1. Connector rings 7 and 8 are connected respectively to the lower ends of strap 5 and rings 9 and 10 are connected respectively to the lower ends of strap 6. A pair of central longitudinal straps 11 and 12 connect the medial portions of head and nose straps 5 and 6 and are disposed in spaced parallel relation. The ends of said straps 11 and 12 are fixed respectively to the head and nose straps 5 and 6 as by being riveted thereto.

A pair of lower longitudinal straps 13 respectively interconnect rings 8 and 9 and rings 7 and 10. A pair of diagonal straps 14 respectively interconnect intermediate portions of straps 11 and

2

and 12 with rings 7 and 8. A second pair of diagonal straps 15 respectively interconnect intermediate portions of straps 14 with rear portions of longitudinal straps 11 and 12.

- 5 A rear closure strap 16 has one end connected to the ring 8 and has a snap 17, the snap 17 being adapted to receive the ring 7 to completely surround the rear portion of the cow's head and securely hold said halter in position thereon. 10 The strap 16 has a length adjusting buckle 16a which will permit the halter to be adjusted to fit cows of various sizes. A forward closure strap 18 has one end connected to ring 9 and has a snap 19 at the other end thereof; said snap 19 being adapted to receive the ring 10 to extend under the cow's throat and embrace the same to hold said nose strap 6 securely against the upper nose portion of the cow.

The above described halter is more or less conventional in design and is only a part of my present invention in that it cooperates therewith to hold the same in place. In the form of my invention illustrated, I provide a pair of cross bars 20 which are disposed at substantially right angles to the spaced longitudinal straps 11 and 12 and interconnect the upper portions of said straps, said bars 20 being disposed in spaced relation to each other. A pair of bolts 21 connect each of said bars 20 with their respective portions of parallel straps 11 and 12. Each of the bolts 21 has a large head which projects outwardly a slight distance beyond said bars 20. A nut 22 as best shown in Fig. 3 is threadably engaged on each of the bolts 21 and securely holds the same in place. The inner ends of bolts 21 are tapered to a rather dull point on projection and the nuts 22 are adapted to be screwed down beyond said points to leave the points projecting inwardly there beyond to form head engaging prongs. 30 A resilient pad such as the sponge rubber pad 23 is connected to each of the bars 20 intermediate the two bolts 21 to normally hold the prongs in slightly spaced relation from the head of the cow. A bolt and nut 24 connect said sponge rubber 23 to the medial portion of bar 20 as best shown in Fig. 3.

The bars 20 are so disposed that when the cow uses her head to butt another cow, the heads of the bolts 21 will engage against the other cow and press the pointed prongs against the head of the "boss" cow. This will cause the "boss" cow great pain without seriously injuring her and will soon break her of butting the other cows.

It will be seen that I have provided an extremely simple yet highly efficient boss cow tamer which will very efficiently stop the boss cows from injuring the other cows in the herd. It will also be seen that by providing the prongs 21 affixed to the harness, that a cow may be effectively and securely tied by a rope or chain

fastened to the lower part of the halter and tension produced in the rope by the cow trying to wander off will compress the sponge rubber and project the prongs against the cow's head to limit the amount of force which she will be willing to exert on the rope and thus prevent her from breaking away.

It will, of course, be understood that various changes may be made in the form, details, arrangement and proportions of the parts without departing from the scope of my invention.

I claim:

1. For use with an animal halter to discourage butting of the animal, a cross bar member mounted on the halter for engagement with the head of the animal, said cross bar comprising an intermediate resilient pad, pointed projections mounted on said cross bar, at least one projection being arranged opposite the ends of said pad, said pad being of a thickness so that its inner animal-contacting surface portion projects beyond a plane passing through the pointed ends of said projections whereby normally the pointed ends of the projections are maintained out of contact with the head of the animal on which the halter is arranged, said pad being adapted to yield under pressure to present the pointed ends of said projections for engagement with the head of the animal.

15

20

25

2. A cross bar member for an animal halter as claimed in claim 1 wherein said resilient pad comprises sponge rubber.

3. A cross bar member for an animal halter as claimed in claim 1 wherein said bar comprises a substantially rigid base portion on which said pad and said projections are mounted, and wherein a plurality of said cross bars are spacedly arranged on the halter portion which is adapted to engage the top and forehead part of the animal.
